UNITED STATES PATENT OFFICE.

JOHN C. STREIBICH AND GEORGE F. GRUVER, OF LITTLE ROCK, ARKANSAS.

SUBMERSIBLE WATER-POWER DEVICE.

1,350,187.

Specification of Letters Patent. Patented Aug. 17, 1920.

Application filed September 2, 1918. Serial No. 252,282.

To all whom it may concern:

Be it known that we, JOHN C. STREIBICH and GEORGE F. GRUVER, citizens of the United States, and residents of Little Rock, 5 in the county of Pulaski and State of Arkansas, have invented certain new and useful Improvements in Submersible Water-Power Devices, of which the following is a specification.

10 Our invention relates to water power development, and its object is to utilize the power of running streams without the necessity of providing dams, races, canals or the like.

15 Our invention consists in the combination of parts and in the details of construction and arrangement of parts as will herein-after be more fully described and claimed.

In the drawing:

20 Figure 1 is a diagrammatic plan view of the device embodying our invention;

Fig. 2 is a vertical longitudinal section on a plane corresponding to the line 2—2 of Fig. 1;

25 Fig. 3 is a detail perspective view of the water-wheel and parts of the casing and power transmission mechanism; and

Fig. 4 is a partial circumferential section through the water-wheel.

30 As we prefer to construct our invention, the casing or flume 1 has the preferably widened inlet end 2 from which the interior conduit 3 leads horizontally to the upper part of the wheel chamber 4 above the 35 water wheel 5, which is fixed on a vertical shaft 6 journaled in an upright frame 7 which stands across the wheel chamber 4. The outlet 8 from the casing 1 leads from a space in the bottom of the wheel chamber 40 below the wheel 5.

Fixed on the upper end of the shaft 6 above the upper part of the frame 7 is a bevel gear 9, and a shaft 10 is journaled horizontally in suitable bearings 11 on the 45 top of the frame 7 and has a bevel gear 12 meshing with the bevel gear 9.

This casing or flume is placed on the bottom 50 of the river or other flowing body of water 14, and the shaft 10 extends over to the bank 15 of the river where it operatively connects with suitable means to utilize the power transmitted through the shaft 10 from the rotating water wheel 5. In the present example, a dynamo electric

55 machine 16 and its current distributing apparatus 17 are illustrated diagrammatically in Figs. 1 and 2; the shaft 10 entering a pit 18 near the edge of the river bank 15, and carrying a pulley 19 which has a belt 20 running up to the pulley of the electric machine 16 suitably supported and housed above the pit 18.

A gate 21 is hinged at one side of the horizontal passage 3 where the water passes to the water wheel 5 and may be swung 65 across this passage to close it or may swing back against the side of the casing. As here shown, the closing of this gate is effected by means of a cable 22 connected to the gate near its free end, and passing over 70 a roller 23 on the casing side and over to the river bank 15 where it is connected to suitable manipulating apparatus 24.

It will be understood that the illustrations of Figs. 1 and 2 are diagrammatic in that 75 the casing 1 and immediately associated and inclosed parts are on a much larger scale than the river and the installations on the bank. In practice, the entire casing and associated parts would be of about the same length up 80 and down the river as the pit 18, and the manipulating means 24 would be contained in the building with the power distributing plant, which may have any other suitable arrangement.

85 The inlet end 2 of the casing 1 which, of course, is placed up-stream, is preferably provided with a grating 25 to prevent the entrance of substances which would obstruct the operation of the water wheel or clog the 90 passages of the casing. As here shown, this grating has a frame with a triangular base pointing up-stream at the middle of the casing, and having a ridge-pole 26 extending up from the pointed end of the bottom of the frame to the middle of the top of the casing; and slats 27 run horizontally from the sides of the casing to this ridge-pole. The horizontal arrangement of the slats is deemed preferable as presenting less obstruction to the inflow of water to the 95 casing.

100 The water wheel 5 is a relatively wide and low cylindrical structure provided internally with a plurality of radial vanes 28 which incline at an angle of about forty-five degrees from near top to bottom of the wheel structure. Preferably, each vane 28

has a short slanting fin 29 along its upper edge extending back over its inclined upper side. As many series of these vanes as may be desired may be provided in succession 5 radially of the wheel. As here shown, there are three such series, and the wheel has the outer cylindrical shell 30 and the shells 31, 32 and 33 arranged in succession inwardly from the outer shell 30 to the shaft 6 and 10 about equally spaced from each other and from the outer shell 30 and the shaft 6. In the three spaces between the shells are the several series of vanes 28 held in their inclined positions by having their lateral edges suitably fixed to the respective shells. 15 A suitable spider 34 fixed on the shaft 6 has arms fixed to the innermost shell 33, and thus supports the wheel on the shaft so that the wheel and shaft rotate together.

20 The gear on top of the frame 7 is inclosed in a water-tight gear-box 35, and the device is preferably so constructed that this gearbox and the frame and wheel may be lifted bodily out of the casing for inspection, cleaning or repairs, the shaft 10 swinging up with these parts when its bearing near the pulley 19 is loosened. As here shown, the apparatus is mounted in this manner by having the upright sides of the frame 7 slidable 25 vertically in upright channels 36 in the inner surfaces of the respective sides of the wheel chamber 4 (Fig. 3). Worm gears may be 30 substituted.

The wheel is rotated by the pressure and 35 impact of the water of the flowing stream 14 diverted into the widened inlet end 2 of the casing 1 and flowing therefrom through the wheel 5 and out through the outlet 8. The 40 backwardly extending fins 29 along the upper edges of the blades or vanes 28 form pockets which add to the impelling effect of the water which, by its momentum, tends to flow across the top of the wheel. The water in acting upon the vanes takes somewhat 45 the course indicated by the arrows in Fig. 4.

This machine does not require a dam or race or chute to get its power. Simply by submerging it in a stream of water in the channel, the water passing through creates 50 the power which can be distributed to any plant that uses power. We have shown the device installed horizontally, but it will be understood that the wheel will run in practically any position in which it is submerged; 55 but it gives more power when it lies down and forms a channel as shown in the casing.

We have found in practice that a device 60 constructed according to our invention in which the water wheel is only about seven inches in diameter will raise forty-five pounds when submerged in a stream of water flowing about three miles per hour. It is not essential to submerge it very deep except that it should be placed far enough below 65 the surface of the water not to interfere with

the running of boats in the stream. It will be understood that the stream would be considerably deeper in proportion, as shown in Fig. 2; the device itself being shown on a larger scale in proportion to the surroundings for purpose of clearness, as hereinbefore alluded to.

While certain constructional details are deemed preferable in connection with our invention; and we have shown and described 75 these rather specifically in elucidating the construction and use of our invention, as is required, we do not wish to be understood as being limited to such precise showing and description, but having thus fully described 80 our invention, what we claim as new and desire to secure by Letters Patent is:

1. In a submersible water power device, a casing having an inlet end and an outlet end, and an intermediate inclosed cylindrical wheel chamber with a passage from the inlet end into the upper part of said chamber, and a passage to the outlet end from the lower part of said chamber of unreduced cross-sectional area from the lower part of 90 said chamber to the exterior of its down-stream end, a water wheel, and mountings for said wheel whereby said wheel rotates in a plane across said cylindrical chamber between the inlet and outlet passages, said 95 water wheel comprising a series of vanes inclined to its axis, each series being confined between cylindrical vertical shells and each vane slanting downwardly and rearwardly from top to bottom with reference to the entrance of the water which passes therethrough, and power transmitting means operatively connected to said water wheel and extending laterally from said casing for operative connection to suitable power distributing means, a frame slidable into and out of said wheel chamber and supporting said water wheel and said operative connection, and a water-tight box surrounding said operative connection on said frame, said box 100 being removable from said casing along with said frame and said water wheel.

2. In a submersible water power device, a casing having an inlet end and an outlet end, and an intermediate inclosed cylindrical wheel chamber with a passage from the inlet end into the upper part of said cylindrical chamber, and a passage to the outlet end from the lower part of said chamber of unreduced cross-sectional area from the lower part of 115 said chamber to the exterior of its down-stream end, a water wheel, and mountings for said wheel whereby said wheel rotates in a vertical plane across said chamber between the inlet and outlet passages, said water wheel comprising a series of vanes inclined to its axis, and power transmitting means operatively connected to said water wheel and extending laterally from said casing for operative connection to suitable 120 power distributing means, a frame slidable into and out of said wheel chamber and supporting said water wheel and said operative connection, and a water-tight box surrounding said operative connection on said frame, said box 125 being removable from said casing along with said frame and said water wheel.

power distributing means, the inlet portion of said casing having tapering side walls leading to said interior conduit, a gate hinged at one side of said casing in the tapered passage from the inlet end to the wheel chamber and adapted to swing across said passage against the outwardly tapering wall of said passage to close it, and manipulat-

ing means connected to said gate for closing it.
